CLAIM

The ornamental design for a group of gilt-edge sheets, as shown and described.

DESCRIPTION

FIG. 1 is a top perspective view of a group of gilt-edge sheets, showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is an end elevational view thereof from the right of FIG. 2; and,

FIG. 7 is an end elevational view thereof from the left of FIG. 2.

No claim is made to the appearance of the structure shown in broken lines.

The claim is directed to the design for a group of sheets in the visual and spatial relationship shown in the drawings.
